AUTOMATIC LUBRICATOR

Thomas H. Boyd, Fayetteville, Ark., assignee of one-fourth to F. C. Harra, and one-fourth to Laut Campbell, both of Springfield, Mo.

Application August 24, 1936, Serial No. 97,561
Renewed February 3, 1940

9 Claims. (Cl. 123—196)

This invention relates to automatic lubricators for internal combustion engines, and particularly that type of mechanism designed to lubricate the upper cylinder walls, upper portion of the pistons, and all adjoining parts of the engine by the employment of vapors evolved in the crank case or valve case of the engine.

10 The primary object of this invention is the provision of an automatic lubricator for internal combustion engines having valve structure for controlling the passage of oil vapors from within one portion of the internal combustion engine to another interior portion thereof, which valve structure is operated through the medium of heat generated by the engine within its exhaust manifold.

Another important object of this invention is the provision of an automatic lubricator, having as a part thereof, a pipe line which extends from a suitable chamber within the engine wherein oil vapors are evolved to the intake manifold so that such vapors might be injected into the upper portions of the cylinders with the charge of combustible fuel, said pipe line having interposed therein, valve means operable by the change in temperature of the exhaust manifold, to the end that variation in the speed of the engine will relatively alter the position of the valve and, therefore, the amount of vapor passing through the pipe line.

A yet further aim of this invention is the provision of unique valve structure for automatic lubricators, which has thermostatic means therein for actuating the valve member so that it may open and close the pipe line of the lubricator as the temperature within the housing for the thermostat changes as a result of operating the engine at high or low speeds.

40 A still further object of the invention is to provide a simple, strong and durable valve for automatic lubricators, that is efficient in operation; wholly automatic in action; controlled by the temperature change within the exhaust manifold; has a number of unique inter-related parts; is easy to apply; and will serve its purpose without attention or adjustment after installation.

50 A large number of minor objects will appear during the course of the following specification, referring to the accompanying drawing, wherein only the preferred embodiment of the invention is illustrated, and wherein:

Figure 1 is a side elevation of a conventional type internal combustion engine, with the auto-

matic lubricator, made in accordance with this invention, combined therewith.

Fig. 2 is an enlarged, detailed, vertical, sectional view through the valve structure of the lubricator.

Fig. 3 is a vertical section, taken along line III—III of Fig. 1.

Fig. 4 is a cross section, taken along line IV—IV of Fig. 2.

Fig. 6 is a sectional view, taken along line V—V of Fig. 2, and,

An automatic lubricator embodying this invention utilizes evolved oil vapors which nor-

vention utilizes evolved oil vapors which normally are exhausted through some suitable vent or breather pipe, and these vapors, with their lubricating qualities, are injected into the explosive mixture just prior to its entrance into the combustion chambers of the engine cylinders. 20

The speed with which the vapors are so introduced, and therefore, the volume of lubricant that reaches the combustion chambers, is varied in direct proportion to the speed of the engine. At slow speeds the exhaust manifold is comparatively cool and, therefore, the hereinafter described thermostatic valve is not opened as wide as when the heat of the exhaust manifold has acted upon the thermostat to completely open the valve when the engine is running at a high rate of speed. 25 30

The automatic lubricator may be combined with any conventional type engine E, having a crank case 8, intake manifold 10, and exhaust manifold 12, with which the parts of the lubricator are directly associated. It is known that the intake manifold 10 is in direct communication with the cylinders formed in engine E and that any vapor injected into manifold 10 will reach the cylinders and contact the walls thereof. A pipe line, comprising pipes 14 and 16, interconnects crank case 8 and exhaust manifold 10, as exemplified by Fig. 1. Manifestly, the exact points of connection might be varied so long as the concepts are followed with respect to conducting evolved vapors from the point of formation to a place where they will be directed into the cylinders above the pistons. The unique valve structure 18 is interposed in pipe line consisting of pipes 14 and 16, and this valve structure comprises an outer sleeve 20, having an intake port 22 and an outlet port 24 formed therein. These ports 22 and 24 are in communication with the ends of pipes 14 and 16 respectively and internally threaded bosses 26 and 28

provide means for interconnecting outer sleeve 20 and the said pipes.

It is preferred that intake and outlet ports 22 and 24 be diametrically opposed so as to be in communication with diametrically opposed openings 30 formed through the wall of inner sleeve 32. Inner sleeve 32 is in telescoping relation with outer sleeve 20 and may be rotated about its axis so as to offset openings 30 with respect to intake and outlet ports when it is desired to prevent the flow of vapors through pipes 14 and 16. This rotation is limited by a pin 34, carried by head 36 of inner sleeve 32, and projecting into an arcuate notch 38 formed in outer sleeve 20.

Shoulders 40 bear against pin 34 to describe the ends of its path of travel and head 36 is knurled so that it is not necessary to employ special tools to turn inner sleeve 32. The under side of head 36 is provided with an annular groove 42, which receives the upper annular end of outer sleeve 20.

Inner and outer sleeve are in frictional engagement, but in order to increase this frictional engagement and provide a lock that prevents accidental removal of inner sleeve 32 from outer sleeve 20, there is presented a crescent-shaped spring finger 44. This member 44 floats in an annular groove 46 formed inwardly from the outer face of inner sleeve 32, and the ends of member 44 bear against the inner face of outer sleeve 20. Obviously, there is a difference in radius between member 44 and inner face of outer sleeve 20 that permits the relationship just described, and illustrated in Fig. 5.

A valve member 48 is reciprocably carried within inner sleeve 32. This member 48 has a groove 50 formed intermediate the ends thereof and moves to and from communication with openings 30 as the temperature within housing 52 is varied. Valve member 48 is urged downwardly by spring

54 that is positioned as shown in Figs. 2 and 3, and the lower end of member 48 projects into housing 52 and against suitable thermostat strips 56 and 58. These strips are supported by a block 60 that is carried within housing 52 and the area of support is intermediate the ends of the thermostat strips. Strips 56 arch as illustrated in dotted lines of Fig. 2 when the temperature rises within housing 52 and strip 58 remains straight. The reason for the use of block 60 becomes obvious when it is understood that very low temperatures tend to arch lower strip 56 so that the ends thereof will move downwardly.

Each of strips 56 and 58 is provided with holes for the reception of guide pins 62 so that dis- placement of the strips is precluded.

Thermostat housing 52 has an open side that is closed by the wall of exhaust manifold 12 when in operative position. An opening 64 formed in another side of housing 52 insures circulation within the housing when the open side thereof has been closed by the wall of the exhaust manifold. In some instances, the form of manifold 12 requires that an adapter be employed, but such device is not here illustrated because of the widely varying requirements caused by different models of engines. As the temperature rises in housing 52, thermostat strips 56 will arch and open the valve by moving valve member 48 up to the position shown in dotted lines of Fig. 2, and as the temperature lowers, the valve member will be dropped to the closed position illustrated in Fig. 2.

Having thus described the invention, what is claimed as new and desired to be secured by Letters Patent is:

1. In an automatic lubricator for internal combustion engines, a valve structure comprising a housing; a sleeve on the housing provided with an inlet port and an outlet port; a reciprocable valve member, having a groove formed therein, within the sleeve and movable to and from a position where the groove is in communication with said inlet port and the outlet port; and a thermostat within the housing for actuating the valve member to the aforesaid position as the temperature of the engine rises appreciably due to heat generated by its operation.

2. In an automatic lubricator for internal combustion engines, a valve structure comprising a housing; a sleeve on the housing provided with an inlet port and an outlet port; a reciprocable valve member, having a groove formed therein, within the sleeve and movable to and from a position where the groove is in communication with said inlet port and the outlet port; a thermostat within the housing for actuating the valve member to the aforesaid position as the temperature of the engine rises appreciably due to heat generated by its operation; and a spring to yieldably urge the valve member from the aforesaid position as the temperature of the engine lowers.

3. In an automatic lubricator for internal combustion engines, a valve structure comprising a thermostat; an outer sleeve provided with an inlet port and an outlet port; an inner sleeve in telescoping relation with the outer sleeve, having openings through the side wall thereof; and a valve member reciprocably carried within the inner sleeve having a groove formed therein and movable by the thermostat to and from a position where the groove is in communication with said openings as the temperature of the engine rises and falls respectively during operation.

4. In an automatic lubricator for internal combustion engines, a valve structure comprising a thermostat; an outer sleeve provided with an inlet port and an outlet port; an inner sleeve in telescoping relation with the outer sleeve, having openings through the side wall thereof; and a valve member reciprocably carried within the inner sleeve having a groove formed therein and movable by the thermostat to and from a position where the groove is in communication with said openings, said openings in the inner sleeve being in communication with the inlet and outlet ports when the inner and outer sleeves are in the normal position, said thermostat adapted to move the valve member as the temperature of the engine rises and falls during operation of and after the engine is started.

5. In an automatic lubricator for internal combustion engines, a valve structure comprising a thermostat; and outer sleeve provided with an inlet port and an outlet port; an inner sleeve in telescoping relation with the outer sleeve, having openings through the side wall thereof; and a valve member reciprocably carried within the inner sleeve having a groove formed therein and movable by the thermostat to and from a position where the groove is in communication with said openings, said openings in the inner sleeve being in communication with the inlet and outlet ports when the inner and outer sleeves are in the normal position, said inner sleeve being rotatable about its axis to close said inlet port and the outlet port.

6. In an automatic lubricator for internal combustion engines, a valve structure comprising a thermostat; an outer sleeve provided with

an inlet port and an outlet port; an inner sleeve in telescoping relation with the outer sleeve, having openings through the side wall thereof; and a valve member reciprocably carried within the inner sleeve having a groove formed therein and movable by the thermostat to and from a position where the groove is in communication with said openings, said openings in the inner sleeve being in communication with the inlet and outlet ports when the inner and outer sleeves are in the normal position, said inner sleeve being rotatable about its axis to close said inlet port and the outlet port, said inner and outer sleeves having yieldable friction means therebetween for precluding accidental relative movement.

7. In an automatic lubricator for internal combustion engines, a valve structure comprising a thermostat; an outer sleeve provided with an inlet port and an outlet port; and inner sleeve in telescoping relation with the outer sleeve, having openings through the side wall thereof; and a valve member reciprocably carried within the inner sleeve having a groove formed therein and movable by the thermostat to and from a position where the groove is in communication with said openings, said openings in the inner sleeve being in communication with the inlet and outlet ports when the inner and outer sleeves are in the normal position, said inner sleeve being rotatable about its axis to close said inlet port and the outlet port, said sleeves having a movement limiting means therebetween.

8. In an automatic lubricator for internal combustion engines, a valve structure comprising a housing; a sleeve on the housing provided with an inlet port and an outlet port; a reciprocable valve member, having a groove formed therein, within the sleeve and movable to and from a position where the groove is in communication with said inlet port and the outlet port; and a thermostat within the housing for actuating the valve member to the aforesaid position, said thermostat being a plurality of superimposed strips, said housing having a block therein for supporting the strips intermediate the ends thereof.

9. In an automatic lubricator for internal combustion engines, a valve structure comprising a housing; a sleeve on the housing provided with an inlet port and an outlet port; a reciprocable valve member, having a groove formed therein, within the sleeve and movable to and from a position where the groove is in communication with said inlet port and the exhaust port; and a thermostat within the housing for actuating the valve member to the aforesaid position, said thermostat being a plurality of superimposed, perforated strips, said housing having a block therein and guide pins extending through the perforations of said strips, said block and guide pins being intermediate the ends of said strips.
